[57] CLAIM

The ornamental design for a skate sidepocket backpack, as shown and described.

DESCRIPTION

FIG. 1 is a perspective view of a skate sidepocket backpack showing my new design;

FIG. 2 is a front elevational view thereof;

FIG. 3 is a rear elevational view thereof; and,

FIG. 4 is a perspective view thereof, with the sidepocket shown in an expanded condition to receive a skate.

The broken-lined showing of skates is for illustrative purposes only and forms no part of the claimed invention. Other broken lines represent stitch lines. The bottom is plain and unornamented.
